UNITED STATES PATENT OFFICE.

CHARLES A. BENNETT, OF TAUNTON, MASSACHUSETTS.

DESIGN FOR A MOUNTING FOR SILVERWARE OR SIMILAR ARTICLES.

SPECIFICATION forming part of Design No. 36,298, dated April 28, 1903.

Application filed March 7, 1903. Serial No. 146,764. Term of patent 14 years.

To all whom it may concern:

Be it known that I, CHARLES A. BENNETT, of Taunton, in the county of Bristol and State of Massachusetts, have invented a new, original, and ornamental Design for a Mounting for Silverware or Similar Articles, of which the following, taken in connection with the accompanying drawing, is a specification.

The annexed drawing illustrates a plan view of the mounting; and the leading or material feature of my ornamental design consists of a scroll at the opposite ends of the mounting and a flower connected by its stem to one of the scrolls, the bloom of the flower occupying the space between the scrolls.

Having described my invention, what I desire to secure by Letters Patent is—

The ornamental design for a mounting for silverware and similar articles as herein shown and described.

In testimony whereof I have signed my name to this specification, in the presence of two subscribing witnesses, on this 10th day of February, A. D. 1903.

CHARLES A. BENNETT.

Witnesses:

GEORGE E. CHAMBERS,
WILLIAM B. GRANFIELD.
